UNITED STATES PATENT OFFICE.

JUDSON MC FELL, OF CHICAGO, ILLINOIS.

ELECTRIC SIGNALING MEANS.

1,194,525

Specification of Letters Patent. Patented Aug. 15, 1916.

Application filed December 21, 1912. Serial No. 737,969.

To all whom it may concern:

Be it known that I, JUDSON MC FELL, a citizen of the United States, residing at Chicago, in the county of Cook and State of Illinois, have invented certain new and useful Improvements in Electric Signaling Means, of which the following is a specification.

My invention relates to improvements in electric signaling means, and more particularly, in some of its features, to means for the annunciation of selected signals at signal-receiving stations relatively remote from a common or central transmission station.

Systems embodying, in whole or in part, my invention hereinafter described, may be employed for many uses, as in hospitals, offices, factories, and other places, for the annunciation of selected code signals; but one use for which my invention is very advantageously available is the provision of a store-service signal-system for calling employees. I have therefore shown my invention in a single embodiment especially adapted for such use, as means of full disclosure, although not intending thereby to limit my invention to such particular use, or to the specific structures illustrated further than as pointed out in the claims.

Primarily, it will be understood that in a department store, for example, there may be a dozen or more persons whose attendance in different parts of the store may be demanded from time to time. Such persons should be subject to call, wherever they may be in the store, and it is advantageous that their calls be transmitted from a common or central station, preferably at the telephone switch board, in order that the person called may promptly attend at the central station or call up by telephone for instructions or to ascertain where he is wanted.

It is advantageous in an electrical signaling system installed for the purpose of annunciating calls throughout a relatively large area, or at a large number of receiving stations, as is the case in a department store, that the calling mechanisms be wholly under the control of the central operator both to initiate and to erase the call signals and that a signal once set shall remain set until intentionally erased by the central operator. In such an installation it is important that the manual operations required of the central operator for the performance of the

signaling duties be simple and capable of easy and rapid performance. Likewise it is obviously important that the wiring extending throughout the building be simple, inexpensive, and not apt to get out of order and that the operating devices themselves be rugged, certain in operation, and of simple construction. Many other desiderata must be attained in order to provide a satisfactory system, and many advantages arising from the practice of my invention will be apparent to those skilled in the art from the following description.

In general one of my objects is to provide a signal system wherein the primary annunciation is visually effected as, for instance, by the display of lights in such relations or positions as to have code meanings, the display of each particular light indicating the call of a certain person or otherwise having some known meaning. Supplementally or alternatively, for some of the practices of my invention, a code signal may be given by the flashing of lights to indicate number signals or by aural annunciation of number signals by gongs or the like. The stations at which the annunciation is effected may be installed in any desired number and location, and where the display of distinctive lights, or lights in distinctive positions, is employed as a medium of annunciation, each announcing cabinet is provided with a selectively operable electro-responsive means or selector for controlling the light display. It is my preference, and I regard it as highly advantageous, so to construct the light controlling means and the selectively operable electro-responsive devices that a plurality of signals may be displayed contemporaneously, and that each may be independently erased as a result of central station operation.

The various receiving station apparatuses are connected by simple wiring with a central station equipment comprising in general an automatic transmitter adapted to transmit selective signaling impulses to the selector over the line wires of the receiving stations, and a controlling key board the key-operations of which govern the operations of the transmitter, and therefore of the receiving instrumentalities, so that each operation of the central operator in initiating and erasing signals may be performed by the simple depression of an appropri-

ately selected key upon a key board. And though there is a separate key for each annunciator-operating part, the wiring is minimized because of the utilization of the 5 selectors at the receiving station, the annunciators controlled by said selectors all acting in response to signals transmitted over the same lines.

In the accompanying drawings wherein 10 I have illustrated an embodiment of my invention Figure 1 is a diagrammatic view of a system embodying my invention and involving, for illustrative purposes, two signal receiving stations; Fig. 1^a is a detail of 15 the keyboard; Fig. 2 is a plan view of a transmitter mechanism; Fig. 3 is a section taken on line 3—3 of Fig. 2; Fig. 4 is a section taken on line 4—4 of Fig. 2; Fig. 5 is a plan view with parts in section of a portion 20 of the annunciating cabinet and a signal receiving station; Fig. 6 is an enlarged detail of the restoring member; Fig. 7 is an enlarged perspective view of portions of the annunciating cabinet and its contained mechanism; Fig. 8 is a detail of certain of the selector mechanisms in one position; Fig. 9 is a view showing the same parts in another 25 position; and Fig. 10 is a detail in elevation with parts broken away showing a portion 30 of the selector mechanism.

In the system as shown in Fig. 1 it may be assumed that there are 12 persons whose calls are to be controlled, as indicated by the twelve large signal-light apertures of 35 the signal annunciating cabinet shown at the extreme right of the view, although the transmitter mechanisms for but two parties are shown in detail.

The central station apparatus comprises 40 in general a key board 15 whereon all of the keys are suitably collocated and this board, in commercial practice, may be conveniently located on the table of the telephone switch-board operator. This key-board provides a signal initiator or calling key 16,—and, preferably, a companion releasing key 17,—individual to each party to be called, or to the visual annunciator to be operated by the selectors, and it preferably 45 provides further a clearing-out key 18 and a special key 19 for purposes to be described, so that all that appears at the central operator's desk in a 12-call installation will be the 26 keys. For purposes hereafter stated, 50 a concealed switch is preferably provided on the key-board arranged to be opened, to remain open, each time a releasing key 17 is depressed, and to be closed, to remain closed, each time a calling key 16 is de- 55 pressed. Such switch, indicated at 20 may be automatically caused so to operate by the provision of a pivoting leaf or rocker plate 21 beneath the bank of keys 16—17, said pivoted member having a link connection 22 60 with the blade of the switch 20 so that the

depression of any key 17 will tilt the plate 21 to open the switch 20 while the depression of any key 16 while the switch 20 is open will oppositely depress the plate 21 to close said switch.

The transmitter 24 illustrated is preferably wholly automatic, subject to control only from the key-board, and, with all its appurtenant parts, it may be located adjacent to the key-board for economy in wiring, although its position may be concealed and out of the way. In general the transmitter preferably comprises a driving electromotor 25 geared down through gearing 26 and 27 to drive the main transmitter 70 shaft 28 on which are mounted the signal wheels. A main signal wheel 30 is provided for each person or for each annunciator to be controlled by the receiving station selector, and preferably each such wheel is supplemented with a companion wheel 31, for supplemental signaling purposes, or "direct" 75 annunciation through annunciators which are not selector-controlled, all of the wheels being secured on the shaft 28 to rotate in unison. Cam wheels on the shaft 28 are provided as at 32, 33, 34, and 35, for purposes to be later described. A four-point snap switch 36 is also preferably provided, 80 as a matter of refinement, to be driven relatively rapidly as the shaft rotates, the construction shown in Fig. 2 arranging such switch 36 on the pinion-shaft of gear 27. In Fig. 1, for simplicity of illustration, I have shown this switch transferred to the opposite end of the shaft together with the gear 27, and have shown the motor direct connected to the shaft 28.

The wheel, 30, of each pair provided on the shaft, has on its periphery a series of 105 teeth in continuing sequence, the sequential number for each wheel being one greater than that preceding it. The two wheels shown bear the numbers "3" and "6", illustratively. These wheels 30 control the selector operation at the receiving station in a manner hereafter described. Each wheel 110 31 has upon its periphery a code signal, which may be several times repeated, indicating preferably a plural-digit number signal to be announced directly, as by bells or flashing lamps. The two wheels 31 shown are adapted to send respectively the number 115 21 and the number 33. Each wheel 30 and 31 has associated with it a contact pen, 120 shown at 37 and 38, the two pens appurtenant to each pair of wheels being normally out of the path of the teeth on their wheels and jointly subject to depression into the path of said teeth by the action of an armature 39' operated by a controlling magnet 39 individual to that pair of wheels. Thus by the action of magnets 39 any selected pair of wheels may be conditioned for signaling 125 operation. A high resistance starting 130

magnet 40 is common to the circuit connections (hereafter described) for all of the lower resistance magnets 39, and its armature 41 is arranged to act as a latch for trigger 42 on the upper bar 43 of a pair of switch controlling bars 43 and 44. Thus when the magnet 40 once releases the bar 43 the dropping of said bar closes the several switches appurtenant thereto and said switches remain closed until the cam wheel 34 acting on bar 44 lifts the pair of bars 43-44 upward to such position that armature 41 may reenergize the trigger 42. The cam of the wheel 34 performs this action shortly before the main shaft completes a revolution and then permits the lower bar 44 to drop away to open the switches governed by the bars 43 and 44 just as a complete rotation of the main shaft is accomplished. By suitable circuit connections hereafter described, this mechanism enables the transmitter to control its own operation after its operation is initiated from the key-board. For economizing current I also further provide automatic means by which the contact pens 37 and 38 when once depressed by the armature 39' will be held closed regardless of deenergization of magnet 39 until a substantially complete revolution of the main shaft has been accomplished. To this end I provide for each armature 39' a latch lever 46 pivotally mounted and forwardly pressed by a spring 47 so that a shoulder 48 on the latch presses laterally against a projection 49 of the armature lever. (See Fig. 2.) As soon as the armature lever is depressed the latch 46 is thrown forward so that its head rides over the portion 49 of the armature, holding it depressed until the latch is mechanically restored to its rear-most position. This restoring operation is accomplished through the action of a pin 51 on one of the signal wheels, coöperating with a pivoted finger 52 carried by the latch member, said finger having a knuckle joint with a portion of the latch member which carries it and being so disposed that when the latch is in normal or inactive position said finger is thrown by spring 53 to a position removed from the path of the pin 51, but when the latch lever is thrown forward to operative position said finger is projected into the path of the pin 51. Consequently when the wheel approaches the completion of its cycle of movement its pin 51 engages the finger 52, tilts it to lock the knuckle joint and then, through the locked joint, forces the latch member rearwardly to permit the armature 39' to be spring retracted by the resiliency of the contact pens.

Other features of structure of the transmitter may best be described in connection with their operation, but in general, as will hereafter more fully appear, the transmitter is operable responsive to the keys of the

key-board, the operation of any selected key 16 of the key-board causing the transmitter to start and an appropriate pair of the signaling pens 37, 38, to be brought into coöperative position with their respective wheels 70 30, 31, so that only the signal appropriate to the selected signal initiator 16 is sent. The transmitter operates automatically through a complete rotation of its main shaft so that the signaling pens of the active wheels send their signals over the appropriate line connections and then, at the completion of a cycle of rotation of the main shaft, the transmitter parts are automatically restored to normal condition ready for further operation.

The selective annunciator devices at the receiving stations are intended for selective operation so that, in response to the number of impulses transmitted by the active wheel 85 30, a signal appropriate to the desired initiator 16 is displayed at an annunciator cabinet at each station. In each receiving station there is an annunciator cabinet provided with a selector structure 60 comprising a plurality of movable parts 61, each corresponding with one calling key 16 of the key-board 15, and each movable to set its distinctive signal. In the specific construction shown, such movable parts are the lever 90 arms 61 pivoted on a vertical shaft 62 and carried, for limited oscillation with respect to said shaft, upon the rungs 63 of the ladder-like bearing frames 64 mounted on the bottom of the containing cabinet 65. Each 100 of these parts 61 is movable to display or erase an annunciator signal, and obviously the translation of the movement of these parts into signal-operations may be performed in various ways, but in the specific 105 construction shown each lever arm has link connection 66' with the rock shaft 66 of a shutter 67 for an aperture 68 in the cabinet wall so that by movement of the lever arm 61 the shutter may be opened or closed to 110 expose or conceal the signal aperture 68. Each such aperture, of course, is individual to some particular call, and the apertures are so arranged that any person subject to call may detect at a glance whether his call 115 is displayed or not. To this end I preferably arrange for lighting the interior of the cabinet,—either continuously or when any signal is set,—by a lamp or lamps 70, and I arrange the shuttered apertures 68 in small 120 banks separated or "piloted" by constantly open, readily-distinguishable, pilot apertures 69 to serve as indices or guides for the ready ascertainment of which particular signal aperture is uncovered. Thus in a cabinet 125 equipped with 12 signals, as shown at the extreme right of Fig. 1, the annunciating apertures may be arranged in banks of three each, two banks being arranged one above the other and the constantly open pilot 130

apertures 69 being arranged between the rows so that a pair of the pilot apertures 69 flank each bank of annunciator openings. Any observer, knowing that his call aperture, for example is central of the upper left hand bank, can distinguish at a glance, by the guiding effect of the pilot openings 69, whether or not his call is displayed.

The individual movable parts or levers 61 are governed in their operation by the movements of an operating finger 75, which, in the specific construction shown, is vertically movable into register with the desired lever 61 to be operated, and is susceptible of horizontal reciprocation to actuate said selected lever 61. Within the casing I provide a vertical shaft 76 on which is slidable a cylindrical rack 77 carrying at its lower end a rotatably movable arm 78 to the extremity 20 of which the finger 75 is pivoted. The finger 75 is normally positioned yieldingly in predetermined pivotal position by a pair of springs 79 so that it may yield transversely with respect to its line of horizontal reciprocation. The arm 78 is vertically movable with the cylindrical rack 77 and is laterally reciprocable with a yoke-frame 80 which is pivoted on the shaft 76 and has in the vertical member thereof a slot 81 in which the 30 extremity of arm 78 engages. The finger 75 receives its two movements—selective elevation, and actuating reciprocation—from two magnets 85 and 86 (Fig. 5) which I will term the selecting magnet and the actuating magnet, respectively. In general, a selecting magnet 85, operating to elevate the rack 77, first raises finger 75 to position opposing the selected one of the levers 61, the rack being held in such elevated position; and then the 40 succeeding operation of an actuating magnet 86 swings the frame 80 and with it the arm 78 causing the finger 75 to make a horizontal reciprocation which acts upon the selected part 61 to move it. The return movement of 45 the armature of actuating magnet 86 causes a release of the holding devices for the rack 77 so that said rack returns to normal position, making the selective apparatus self-restoring, that it may be ready for another 50 selective operation.

Specifically the armature 87 of magnet 85 carries a live or active pawl 88 pivoted thereto and spring pressed toward the rack 77, the tail of said pawl 88, when the armature lever is retracted, bearing on a fixed stop 89 so as to throw said pawl out of engagement with the rack. The end of the armature lever also preferably bears upon its extremity a stop pawl 90 so that, as 60 shown in Fig. 9, when the armature is attracted, the coaction of the two pawls 88 and 90 with the cylindrical rack positively forces the rack forward one step, but the stop-pawl prevents its over-throwing. When the 65 armature lever 87 is retracted both pawls

are moved out of engagement with the rack, but a holding pawl 91 is provided, to hold the rack in elevated position. Below the tail of pawl 91 is a trip finger 92 drawn upward toward operative position by the 70 spring 93, said finger being pivoted on the armature of actuating magnet 86. The trip 92 is acted on by the rack 77, so that when said rack is in its lowermost position the trip 92 is depressed out of operative relation 75 to the pawl 91, but on the first step of the rack 77 upward, said trip rises to its plane of operative relation to said pawl 91. The construction is such that upon the attraction of the armature lever 95 of magnet 86 80 the tip of trip 92 idly passes the end of the pawl 91, but on the retraction of the armature lever the shoulder on said trip 92 engages the tail of the pawl 91 and throws said pawl out of engagement with the rack, 85 thereby to free said rack for gravity return to normal position, where, striking on the trip 92 it throws said finger out of engagement with pawl 91 and permits the pawl to resume its operative normal position. For 90 operating the swinging yoke 80 the armature lever 95 of the actuating magnet 86 has a simple link connection 99 direct with the frame. Now it will be apparent that when a given number of impulses pass through 95 magnet 85 and then a single impulse passes through magnet 86 the result will be the elevation of the rack through the selected number of steps so that the finger 75 may stand opposite the desired lever 61, this 100 selecting operation being followed by a transverse swinging of the frame 80 which causes finger 75 to perform its operation of moving the selected lever 61, the return movement of yoke 80 due to the retraction of armature 105 of magnet 86 being also accompanied by a releasing action with respect to the holding pawl 91 for the rack 77 whereupon said rack returns to normal position, tripping out the finger 92 which causes the releasing action 110 of pawl 91, so restoring all of the operating parts of the selector mechanism to normal.

It is my preference that two distinct operations of the part 61 be required respectively to set and to release a signal, in order 115 that the signal once set will be allowed to remain displayed as long as the central operator desires,—it being the plan of operation of the system herein specifically disclosed that any selector-controlled signal once set 120 shall be allowed to remain displayed until the desired party has communicated with the central operator, whereupon it shall be the central operator's duty to erase the signal. To this end I prefer that the levers 125 61 be so arranged that when first acted upon by the finger 75 they first operate to open their respective shutters 67, and when next operated upon by the finger 75 in exactly the same way they operate to close the respective 130

shutters, and I so arrange the levers 61 and the shutters, that each lever may hold any position to which it is moved. Specifically I provide in the hub portion of each lever two lateral recesses 61^a and 61^b separated by a peak 61', so that the notch formation is of W-shape. Viewing, for example, Fig. 7, the arrangement of parts is such that when all the shutters are closed the horizontal reciprocation of the finger 75 in the plane of any one of said levers will cause the pointed end of said finger to ride down the left hand side 61^a of the central peak of said lever, throwing said lever to the position shown in dotted lines in Fig. 5, the finger 75 yielding laterally to accommodate this movement. This movement of the lever 61 carries the peak 61' leftwardly of the path of movement of the point of finger 75 so that on the next reciprocation of the finger in the same plane, it strikes on the right-hand incline of the central peak and, sliding down into the right hand recess 61^b, acts to move the lever in opposite direction. This insures that a plurality of reciprocations of the finger 75 in the plane of any given lever 61 will move said lever alternately to open and close its shutter.

It is sometimes desirable to close simultaneously all shutters that may be standing open, so at the bottom of the stand of levers 61, in the plane of the lowest or normal position of finger 75, I provide a lever 95 having a single recess 96, and an extension arm 97 overlying all of the levers 61. When any lever 61 moves to shutter opening position it carries arm 97 of lever 95 along with it. Therefore when lever 95 is restored to normal position arm 97 restores all levers 61 that may be standing in shutter-opening position.

While manifestly various wiring plans might be employed to connect the parts of the apparatus heretofore described, the plan of electrical connection which I prefer is that of making all of the electrical connections by which the keyboard controls the operations of the transmitter local to those two devices and energized by local battery; and making the connections for the lamps, magnets, and bells appurtenant to the signal receiving station connectible with a higher potential source of supply such as city lighting mains, by a minimum number of wires, the essential wires from the transmitter to all of the annunciator cabinets being only three in number.

The call and release keys 16 and 17, for each number, both control a battery circuit which when closed includes the controlling magnet 39 for the appropriate pair of signaling wheels and the starting magnet 40 which is common to all of the starting circuit branches. Specifically battery 100 has wire connections 101 dividing in multiple

branches 102 respectively extending to the switches 103, each of which is susceptible of closure by either the calling key 16 or the release key 17, each multiple branch extending by wire 104 through its appropriate controlling magnet 39, said branches uniting in the wire 105 which extends to the magnet 40 whence connection is made by wire 106 to a switch 107 normally closed by a short cam surface on the insulated wheel 33 on the transmitter shaft, said switch 107 having connection 108 back the battery. When any calling key 16 is depressed the circuit last above described is closed and higher resistance magnet 40 immediately becomes energized attracting its armature 41 releasing the latch 42 to permit switch bar 43 to fall until stopped by bar 44 which rides upon the surfaces of cam wheel 34. The falling of bar 43 closes the three switches 110, 111, and 112. Switch 110 is connected in parallel with the coil of magnet 40 so that said coil is immediately short circuited to increase the current flow through the magnet 39. Switch 111 connects wires 113 and 114, said wire 114 connected through miniature switch-board lamps 115 with wire 116, said wires 113 and 116 being respectively connected to wires 108, 101 so that said miniature lamps, located on the switch-board, are energized from the battery 100, and since they glow during the entire time that the transmitter is running they serve as indicators for the operator as to the condition of the transmitting unit. The operator, of course, after initiating one call, must wait until these lights are extinguished before initiating another call. The switch 112 is contained in wire 118 bridging motor 25 across the supply mains 120-121. Consequently as soon as the switch bar 43 falls closing switch 112 the motor starts in operation, driving the main shaft 28. Immediately upon the commencement of rotation of the main shaft the cam 35 closes the double pole switch 122 which closes the connections of power wires 120' and 121' with the supply mains 120 and 121 respectively. This switch 122 is latched in closed position by latch 123 which acts as an armature for the releasing magnet 124 in circuit with the wire 125 connected between wire 113 and a normally open switch 126, controlled by the clearing out key 18 of the key-board and having continuing connection by wire 127 to wire 101. Thus only by the closure of clearing out key 18 energizing magnet 124 through the circuit 10, 101, 127, 126, 125, 124, 113, 108, 100, can the power circuit switch 122 be opened after once it is closed. As soon as the starting circuit has become energized as before described, causing the closure of switch 110 cutting out the resistance of said magnet from the starting circuit, the lower resistance magnet 39 becomes 130

effectively energized and attracts its armature 39' which is latched in attracted position by the latch lever 46, so throwing the contact pens 37 and 38 into the path of the teeth of their respective wheels 30 and 31. This condition, it will be remembered, maintains until a complete revolution of the main shaft has been effected when the pin 51 on the wheel 31 trips out the latch 46 and permits the springs to raise the structure. This latching mechanism is used to economize battery current, and early in the cycle of revolution of the main shaft the cam 33 permits the switch 107 to open, breaking the starting circuit.

The main shaft and all of its wheels 30 and 31 are connected in signaling circuits, the battery 100 having one of its terminals connected by wire 130 to brush 131 bearing on the main shaft 28. All of the pens 37 for number wheels 30 have multiple connections 133 by common wire 134 to a relay 135 which is connected through wire 136 to the wire 127 which is connected to the opposite terminal of battery 100, so that each time a tooth of wheel 30 coacts with pens 37 it establishes a circuit 100, 130, 131, 28, 30, 37, 133, 134, relay 135, 136, 127, 100, energizing the relay 135. This relay 135 I will refer to as the selector controlling relay as it governs the operation of selectors at the several receiving stations in a manner hereafter described.

All of the contact pens 38 having multiple connection by wires 140 and common wire 141 with relay 142, connected by wire 143, including switch 20, to wire 127 so that obviously as each tooth of the wheel 31 coacts with its pen 38, (providing switch 20 is closed) the circuit for relay 142 is closed and the relay energized. This relay controls the number-signal annunciators—such as gongs and lamps—at the signal receiving stations and I will refer to it as the number-signal relay. Manifestly both relays are dispensable intermediaries for relaying signal impulses from the transmitter to the line, their use obviating all possibility of charging the transmitter with high-potential current which might be dangerous to attendants or damaging to the machine.

For supplying the current to the two magnets 85 and 86 of each signal receiving station selector apparatus, a wire 150 is run from power wire 121' throughout the building to the several receiving stations, for multiple connection with all of said magnets at said stations, separate return wires being provided to connect magnets 85 and 86 respectively with the power wire 120'. All of the magnets 85 are connected in multiple with wire 151 extending back to power wire 120' and including in its course the armature 135' of the selector-controlling relay 135 as a movable member of a normally

open switch. All of the operating magnets 86 of the several selectors are connected in multiple to the return wire 153 which runs to a switch 154 controlled by the cam 32 on the main shaft of the transmitter, said wire 153 also preferably including a normally closed switch 155 governed by the special key 19, and extending from said switch back to the power wire 120'. The cam surface of wheel 32 which closes switch 154 is arranged to act after the signaling operations of the wheels 30 and 30' have been completed, and said cam is arranged to close switch 154 for a sufficient length of time to insure proper energization of the magnet 86. Now it will be apparent that as the main shaft 28 of the transmitter is rotated the active wheel 30 causes a number of impulses to be transmitted through the selector-controlling relay 135 which accordingly closes the circuit 150—151 for the selector magnet 85 at each signal-receiving station, so that the selector rack is stepped up to an appropriate position according to the number of impulses transmitted. Then, after the stepping up action is completed, but before the main shaft of the transmitter completes its single-revolution, switch 154 is closed so that a single impulse is transmitted through the circuit 151—153 which includes the actuating magnets 86 at all of the signal receiving stations. The armature of each said magnet 86 thereupon makes a single reciprocation to operate the appropriately selected lever 61 at each receiving station, and to restore the selector rack 77 to normal position.

The lamps 70 within the respective annunciator cabinets might be caused to glow constantly if desired, by simple direct connection with the power circuit connections 120'—121', but I prefer that the connection be such that the lamp be energized either to flash a number signal, or so as to flicker, to attract attention, whenever a new signal is being sent. To get the flicker effect whenever the transmitter is being operated the rotary snap switch 36 is provided as heretofore described, light wires 160 and 161 being run from the power wires 120'—121' through said switch and multiple connections made from said light wires to the lamps 70 of the respective annunciator cabinets. Only one cabinet is shown so connected in the drawings. Manifestly as long as the transmitter is in operation the rotation of the switch 36 produces a regular make and break of the lighting circuit to flicker the lamps. Whenever the transmitter comes to rest the lamps glow steadily until they are extinguished. If it is desired to have the lamp within the cabinet flash the number signals of wheels 31 said lamps are connected for control from the relay 142. The relay 142 may have two switches controlled by its armature 142', one said switch,

163, being closed whenever the armature is retracted. This switch is connected with a wire 164 extending from the power wire 120' to the several receiving stations for connection, if desired, to the lamps 70 as indicated in the extreme right in Fig. 1, return connection of the lamp being made by common return wire 166 extending back to power wire 121'. Wherever desired supplemental signal lamps 167 may be bridged across the wires 164-166 so that number signals as initiated by the wheels 31 may be visually displayed wherever desired throughout the store by the flashing of the lamp on said circuit. The second switch 170 for armature 142' is preferably arranged to be closed when the armature is in an attracted position, and said switch is contained in the wire 171' running physically parallel with the wire 166 throughout the building, so that gongs or other audible signaling means 172 may be bridged across the wires 166-171 to respond by audible number signals to the circuit closing operations of signal wheels 31. Manifestly as far as the display of the annunciator signals by the openings of the shutters of the cabinet is concerned the wheels 31 and all of the parts affected thereby may be dispensed with. It is usually desired, however, to give both audible and visible signals and with the construction shown both these results may be attained, and at the same time the releasing operations for the cabinet signals effected by operation of release keys 17 may be performed without repeating the audible signals.

Among other dispensable features of my invention, which however are advantageous refinements, is a provision of the shutter closing means controlled by the clearing out key 18, said key, (in addition to the switch 126 heretofore described,) also controlling a switch 180 arranged in the wire 181 which is connected to wire 153 at points on opposite sides of switch 154. Consequently whenever switch 18 is closed the circuit 150-153 for the operating magnets 86 of all the selectors is closed, causing each thereof to make a horizontal reciprocation of the actuating finger 75 so that it may act on lever arm 95 to restore all of the levers 61 to closed position so closing all of the shutters. The closure of the switch 126 by the key 18 completes the circuit from releasing magnet 124 which releases latch 123 and allows switch 122 to open so breaking the power circuit from which the cabinet lights 70 are energized. This key 18 is used only where it is desired for some purpose to erase all signals, as for instance when there is but one signal set and that signal has been answered. Under such conditions, manifestly, it is economical to extinguish the lights in all of the cabinets.

The special key 19 may be used to cause

the transmitter to operate continuously, (but idly, —as far as any operation of the signal wheels 30 and 31 is concerned,) simply for the purpose of causing the switch 36 to make the lights 70 in all of the cabinets flicker to indicate to all observers that there are unanswered calls that require attention. This obviously may be used as an imperative signal, for when the flickering of the cabinet lights continues without new calls being set every observer will know that the operator is pushing the special button 19. The button 19 is provided with a latch 19', shown as a simple feather which slides in the slot in the supporting structure and may be turned to lock the key in lowered position until intentionally released. The depression of the key 19 opens the switch 155 so that the continuous rotation of the main shaft will not cause impulses to be sent through the circuit 150-153 and therefore the actuating magnets 86 of the respective cabinets are not energized. For closing the starting-magnet circuit to insure constant operation of the transmitter a normally-open switch 185 is provided connected by wires 186 and 187 respectively to wires 101 and 105 so that upon closure of said switch by key 19 a starting circuit including magnet 40 is established by the path 100, 101, 186, 185, 187, 105, 40, 106, 107, 108, 100.

In résumé it will be observed that my system provides at the central operator's station a switch-board having a signal-initiating switch (103) individual to each signal intended to be transmitted, and at a signal receiving station a movable part (lever 61) individually corresponding to each said switch and intended to be moved in response to the switch operation. The movement of this movable part (61) is suitably translated in some way into a distinguishable signal, as in this case, by the opening of an appropriate one of a series of shutters (67) for visual display of the casing-contained light through the opened orifice. The closing of any signal initiating switch 103 starts in operation the automatic transmitter by closing a circuit for starting magnet 40 the energization of which permits the closure of switch 112 for the transmitter-driving motor 25. The transmitter causes a number of impulses individual to the particular signal-initiating switch 103 to be transmitted in the signal line for the several signal receiving devices, this operation being accomplished by the energization of magnet 39, individually connected to the selected switch 103, which said magnet conditions the appropriate signal wheel 30 and switch pen 37 for coöperation and thereby causes relay 135 to be energized in accordance with the tooth arrangement of wheel 30 and so to send the appropriate number of impulses in the line circuit 150-151 ex-

tending to all of the selecting magnets 85 at the several signal receiving stations. The magnet 85 controls the selective function of the selector 60, the reciprocations of its armature in response to the number of impulses transmitted to it causing the selector rack 77 to be stepped up so that the operating finger 75 registers with that movable member 61 which is individually appropriate to the selected initiating switch 103. The further automatic action of the transmitter, after this selective function has been performed, closes the circuit for the actuating magnets 86 of the receiving stations, the closure of switch 154 by the transmitter cam 32 establishing the magnet circuit 150-153 appurtenant to said magnet 86. The energization of this magnet 86 moves the selector finger 75 horizontally (through its connection with the yoke 80 connected to the armature of magnet 86) so effecting a movement of the selected movable part 61 with a resultant annunciation of the desired signal. The deenergization of magnet 86 trips (through the operation of the releasing device 92) the holding pawl 91 for the selector rack and permits it to return to initial position, so restoring the selector parts to normal. After one rotation of the transmitter it automatically comes to rest by opening of motor switch 112. It is my preference that the visual signal annunciated as a result of this selective operation shall continue to be set until it be intentionally erased, and that other signals may be set without disturbance of the first. This result is attainable, for one example, with the shutter construction shown. For release of the set signal the same selective function is performed as in setting said signals, and it is my preference that the magnet-moved parts of the selector perform exactly the same actions in releasing a signal as in setting it. Therefore I construct the movable members 61 so that upon similar successive operation of the selector finger 75 with respect to the same part 61, said part will alternately move to set and to erase the signal, this effect being attained by the double recess construction in the hub of the part 61. Consequently to erase any signal set only a second closure of the appropriate switch 103 is requisite. It will be noted that the construction requires no holding devices for levers 61, which will stand still in any position to which they may be moved.

While the system thus far summarized is complete and operative in itself, it is oftentimes preferable in practice to supplement the indirect, or selector controlled visual signal with a direct signal, either an audible or visual number-signal governed by the transmitter-number-wheels. Under these circumstances it is preferable not to employ the same wheel to occasion both the direct

and indirect signals for the reason that while the indirect signaling apparatus may employ a continuing sequence of impulse-numbers for selector operation running up to any desired number, the audible signals should preferably consist of short groups of impulses indicative of plural digit number signals, several times repeated, so as to avoid the possibility of miscount. For this reason a second set of wheels 31 is employed in the transmitter, controlling the energization of relay 142 which governs the circuit 166-171 for the gongs 172 of the several receiving stations and which may also control the lighting circuit 166-164 for giving visual number signals either through the lights 70 within the cabinet or through separate lamps 167. Where these two systems are combined, however, it is important that the operation of the switch 103 to release the indirect, or cabinet signal shall not repeat the call through the auxiliary direct-number-signal devices, (i. e. the gongs and lamps 167,) and it is for this reason primarily that separate calling and releasing keys are employed. The depression of any release key 17 opens the switch 20 which is included in the circuit of relay 142 so that while as far as the transmitter operations and the selector operations are concerned the closure of release key 17 has the same effect as the closure of signal initiating key 16, the relay 142 for the supplemental or "direct" signal devices is disabled by the depression of a release key and remains disabled until some signal initiating key is subsequently depressed to tilt the pivoted frame 21 and again close the switch 20.

The function of the clearing out key 18 is to release simultaneously all indirect, or selector-set signals that may be set in the annunciator cabinets and to extinguish the lights in said cabinets. Depression of the key 18 first closes switch 180, which closes the circuit 150-153 for all of the selector actuating-magnets 186, causing the actuating fingers 75 to make a horizontal reciprocation without any preceding step-up action, thereby to actuate the restoring levers 95 associated with the movable members 61; and then a further depression of key 18 closes the switch 125 to energize the release magnet 124 which releases the switch 122 for the power circuit, to cut off the lighting circuits at said switch 122.

The function of the rotary switch 36 is merely to cause the lights in the cabinets to flicker while the transmitter is in operation, and the function of special key 19 is to permit this flickering to be effected continuously as long as desired without transmission of any signal, said key 19 controlling the switch 185 which will close a circuit for the starting magnet 40 and a switch 155 which will open the circuit 180

150—153 of the selector operating magnet 86.

I have herein described in some detail a particular embodiment of my invention, 5 many of the details of which I believe to be new and useful, but it will be apparent to those skilled in the art that many changes might be made in the construction and arrangement of parts without departure from 10 the spirit of my invention and within the scope of the appended claims.

What I claim is:

1. Selective signaling means comprising, in combination, an operator's key-board having a plurality of self-restoring signal initiators, each individual to a signal to be transmitted; an automatic self-restoring transmitter responsive to each signal initiator to transmit a different signal; suitable line connections from said transmitter to a receiving station, and at the receiving station a plurality of parts to be moved corresponding with the respective signal initiators and each movable to two alternative positions, 25 and a self-restoring selector operatively associated with the line connections and responsive to each line signal to select and actuate from either of its positions to the other the appropriate part to be moved.

2. Selective signaling means comprising, in combination, an operator's key-board having a plurality of switches each individual to a signal to be transmitted and an automatic transmitter comprising an electro-magnet for each key switch, a plurality of signal wheels and line switch mechanism therefor respectively controlled by said key controlled magnet and responsive to the closure of any key switch to transmit the 35 signal impulses individual thereto, suitable line connections from said line switch mechanism to the receiving station and at each receiving station a selector and a plurality of parts to be moved, said parts to be moved 40 respectively corresponding with the several signal initiating switches and said selector comprising means common to all of the parts to be moved to select and actuate the appropriate part in response to each line 45 signal.

3. In a selective signaling system the combination of a central station transmitter operable to transmit predetermined signals, receiving station apparatus comprising a 55 plurality of parts to be moved each individual to one of said predetermined signals and each movable alternatively to two positions, a selector responsive to such predetermined signals to select and actuate from either position to the other, the appropriate part to be moved, and suitable signal line connections between said selector and said transmitter.

4. In a selective signaling system, receiving station apparatus comprising at one 65

station a group of separate annunciating means for giving a number of different signals, a plurality of parts to be moved respectively controlling certain of said signal-annunciating means, electro-responsive 70 means, including a common selecting magnet, for selecting any one of said parts to be moved; electro-responsive means including a common actuating magnet, for actuating the selected part to be moved, circuit 75 connections for said magnets, and a central station transmitter operable to transmit impulses through the selecting magnet to select any desired part to be moved, and to transmit impulses through the actuating 80 magnet to actuate the selected part to be moved.

5. Selective signaling means having in combination, receiving station apparatus comprising separate annunciating means for giving a number of different signals, a plurality of movable parts respectively controlling certain of said signal-annunciating means; a selector comprising means, including a selecting magnet, to select any one of 85 said parts to be moved, a common means, including an actuating magnet, to actuate the selected part to be moved and restore the selector to normal condition, suitable circuit connections from said two magnets 90 to the central station, and central station transmitting means selectively operable to transmit impulses through the selecting magnet for selection of the appropriate part to be moved, and thereafter to transmit an impulse through the actuating magnet for actuation of said parts to be moved.

6. In a selective signaling means, an annunciator cabinet providing a plurality of signal display parts, a plurality of parts to be moved each to cause the display of one of said signals, electro-responsive means common to all of said parts to be moved to select and actuate singly any one thereof, line circuit connections to said electro-responsive means, and, at a transmitting station, a selectively operable plural-impulse transmitter associated with said line connection, and controlling the electro-responsive means to cause the display of any desired signal.

7. In a selective signaling system, line connections extending from a transmitting station to a plurality of receiving stations; at each receiving station an annunciator cabinet having a plurality of signal display parts each individual to a signal, an electro-responsive selector connected with the line connections and operable to select and actuate any one of said signal display parts; at a transmitting station, a transmitter having 120 parts settable for the transmission of different impulse-groups in the line suitable to actuate the selector to select any desired display-part, and keys, individual to respective signal display parts, each controlling the 125 130

transmitter to set it for transmission of the impulse group appropriate to secure response of the corresponding display part.

8. In a selective signaling system, the combination of line circuit connections from a transmitting station to a plurality of receiving stations, at each receiving station an annunciator cabinet having a plurality of movable signal display devices, and electro-responsive means common to all of said devices for selecting and operating the appropriate ones of said devices in response to different numbers of line impulses, and signal transmitting means at the transmitting station comprising an operator's key-board and means responsive to the operation of each key to transmit a line signal appropriate for the selection and actuation of the corresponding display devices at the receiving stations.

9. In a selective signaling system, the combination of receiving station apparatus comprising a plurality of annunciators, a common selecting and actuating means for all of said annunciators operable alternately with respect to each annunciator to set it on one operation and to release it on the next operation, circuit connections for said selector means, other annunciating means directly responsive to code signals in the line, circuit connections for said direct annunciator means, a transmitter selectively operable and coöperating with both said several circuit connections to transmit setting and releasing signals to said selector, and code signals to the other annunciating means, and means whereby said transmitter effects the direct annunciators only when it is setting annunciators through said selector, and not when it is releasing said selector-set annunciators.

10. In a selective signaling system, the combination of receiving station apparatus comprising a plurality of annunciators, a common selecting and actuating means for all of said annunciators including parts to set said annunciator at one selective operation and to release it at the next similar selective operation of said selector; line circuit connections for said selector means and selective transmitting means associated with the lines.

11. In a selective signaling system, a selective transmitter, line connections therefor, a selector connected with the line, a plurality of lamp-illuminated visual annunciators selectively controlled by said selector and means controlled by the transmitter for flickering the illumination of said annunciators.

12. In a selective signaling system, a selective transmitter, line connections therefor, a selector connected with the line, a plurality of lamp-illuminated visual annunciators selectively controlled by said selector and means controlled by the transmitter, and

operable without operation of the selector-operating means, for flickering the illumination of said visual annunciators.

13. In a selective signaling system, a plurality of signal receiving stations each comprising an annunciator cabinet having a plurality of closable openings, a like plurality of parts to be moved for opening and closing said openings, selector means for selecting and operating any one of said parts to be moved, line connections for said selector, and selector controlling plural-impulse signal transmitting means for controlling all of the signals.

14. In a selective signaling system, the combination of receiving station apparatus comprising a plurality of annunciators, common electro-responsive selecting and actuating means for all of said annunciators operable alternately with respect to any annunciator to set it on one operation and release it on the next similar operation, line connections for said selecting-and-actuating means, and central station means for controlling said selecting-and-actuating means.

15. In a selective signaling system, the combination of receiving station apparatus comprising a plurality of annunciators, common electro-responsive selecting and actuating means for all of said annunciators operable alternately with respect to any annunciator to set it on one operation and release it on the next operation, line connections for said selecting-and-actuating means, central station means for controlling the setting of said selecting-and-actuating means individually, and central station means for releasing the annunciators individually or in unison at will.

16. In a selective signaling system, the combination of receiving station apparatus comprising a plurality of annunciators, a self restoring selector common to all of said annunciators, for selecting and actuating any one thereof, said selector operable alternately with respect to each annunciator to set it on one operation and to release it on the next operation and having means for releasing all of the annunciators in unison; circuit connections for said selector and central station means controlling the said operations of said selector.

17. In a selective signaling system, the combination of receiving station apparatus comprising a plurality of annunciators, a self restoring selector common to all of said annunciators for selecting and actuating any one thereof, said selector operable alternately with respect to each annunciator to set it on one operation and to release it on the next operation and having means for releasing all of the annunciators in unison; circuit connections for said selector, and central station means comprising an automatic transmitter associated with the line

to transmit setting and releasing signals to said selector, and means independent of said transmitter for controlling said selector to release all of the annunciators in unison.

- 5 18. In a selective signaling system, a selector comprising a plurality of parts to be moved, a selecting electromagnet common to said parts to be moved for selecting any one thereof; an actuating magnet common 35
- 10 to said parts to be moved for actuating the selected one thereof; a circuit for the first said magnet having a plurality of line switches therein, a circuit for the second magnet having a switch therein and central 40
- 15 station transmitting means comprising a motor driven shaft, a plurality of number wheels thereon for coöperation with the respective line switches and a wheel for coöperation with the switch of the other circuit, 45
- 20 automatic motor stopping means controlled by the shaft, controlling magnets associated with respective line switches to condition them for coöperation with their respective signal wheels, electro-responsive motor 50
- 25 starting means, and a central station key board comprising a key for each signal wheel; a switch controlled by each said key, and circuit connections for each said switch including its respectively appropriate controlling magnet and the motor starting 55
- 30 means.

19. In a signaling system, the combination of a bank of visual annunciators, a plurality of parts to be moved controlling said annunciators, a selector magnet common thereto for selecting any part to be moved, an actuating magnet common thereto, for actuating the selected parts to be moved, a circuit for the first said magnet, a circuit for the second said magnet, and central station means for transmitting different selecting signals in the first said circuit followed by an actuating impulse in the second said circuit.

20. In a selective signaling system, the combination of a plurality of annunciators, a like plurality of operating keys, circuit connections and means to energize the same, selective signal transmitting means responsive to the operation of any key to transmit a corresponding signal; and annunciator selecting and actuating means responsive to any said signal to select and actuate the corresponding annunciator, to set and release such annunciator alternately. 55

In testimony whereof I hereunto set my hand in the presence of two witnesses.

JUDSON McFELL.
